TIMER

Joseph S. Murphy, 1425 S. Sandia Ave.,
West Covina, Calif.

Filed June 3, 1963, Ser. No. 75,181

Term of patent 14 years

(Cl. D42—7)

FIG. 1.

FIG. 2.

FIG. 3.

FIG. 4.

FIG. 1 is a front elevational view of a timer showing my new design;

FIG. 2 is a top plan view thereof;

FIG. 3 is a rear elevational view thereof; and

FIG. 4 is a right side elevational view thereof.

The bottom and left side of the timer, not shown, are substantially similar to the top and right side thereof, respectively.

I claim:

The ornamental design for a timer, as shown and described.
